UNITED STATES PATENT OFFICE.

GOTTLIEB LÜSCHER, OF AARAU, SWITZERLAND.

WATER-LOCK GATE.

No. 884,400.

Specification of Letters Patent.

Patented April 14, 1908.

Application filed April 29, 1907. Serial No. 370,930.

To all whom it may concern:

Be it known that I, GOTTLIEB LÜSCHER, a citizen of the Swiss Federation, residing at Aarau, Switzerland, have invented certain new and useful Improvements in and Relating to Water-Lock Gates, of which the following is a specification.

This invention relates to water lock gates provided with an arrangement for the raising and lowering of the separate gates or flaps without having to enter the water or make use of a boat.

A method of carrying out this invention is shown in the accompanying drawings in which:—

Figure 1 is an elevation of the lock gate with the bed in section; Fig. 2 is a plan of the left half of Fig. 1; Fig. 3 is a section in the direction of the stream; while Fig. 4 is a section on a large scale through I—II (Figs. 1 and 2) of the part of the apparatus built in the river bed; Figs. 5 and 6 are detail views and Figs. 7 and 8 a modification of these details.

The lock arrangement shown consists of a sill *a* built across the stream, of wood, iron or concrete, which may rise to a greater or less extent above the bed of the river *b* and on which is erected a movable wall consisting of separate gates or flaps *c* which may be dropped in the downward direction of the stream (Fig. 4). These movable flaps are secured by pivots *d* on the sill *a* and are maintained in their upright position against the force of the stream by the struts *e*.

For the purpose of lowering or raising the flaps, without having to enter the water or make use of the boat, the following arrangement is provided. Somewhat above (with regard to the stream) the movable lock wall just described, an aerial line is carried across the stream, consisting of a wagon *g* and four runners *f¹* *f²* *f³* and *f⁴*, for example of round or flat iron, or preferably of wire rope. These runners (see Figs. 1, 2 and 3) are anchored at their ends and may be stretched by drums, tightening screws, or automatic arrangements as indicated at *f⁵*. The wagon *g* is hung on the runners by means of rollers and by means of a draw rope can be moved by hand or power to, and held at, any desired position. On the wagon are provided the winding drums *h* and *h¹*. Close to these runners is arranged a line *i* consisting of a hempen rope, strong iron rod or wire rope, which by means of a winding drum *m* may

be let down on the river bed (position *i¹* Fig. 1) or tightened up so that it is raised up through its entire length to the height of the aerial line (position *i²* Fig. 1). On this line hang the raising and lowering chains or ropes of the separate movable flaps *c* of the lock wall, of which there are four, *k¹*, *k²*, *k³* and *k⁴*, for each flap as shown in Figs. 1 and 2. These raising or lowering ropes or chains are fastened with one end on the line and the other end on the respective flaps of the lock wall in pairs on a powerful lever *l* (Fig. 5) which is fitted close to the top edge of the flaps, so that for example, the raising ropes or chains *k³* and *k⁴* catch on the loops *l¹* and *l²* of the lever *l* in Fig. 5. If then the line is lowered from the position *i²* to the position *i¹*, the raising ropes or chains sink with it on to the bed of the river and disappear under the water; if however it is wound up, which as shown in Fig. 1 can be effected by means of the winding drum *m*, it lifts the chains, by means of the ends fastened thereto, upwards, so that they can be reached from the aerial line. If now one of the flaps of the perpendicular movable wall for any reason has to be lowered, for example the third from the left (in Fig. 1), and passage allowed for the flow of the water, this is effected as follows. The line resting usually on the bed of the river is drawn upwards, that is from the position *i¹* (Fig. 1) into the position *i²*, so that the raising chain ends fastened thereto may be reached from the aerial line. The wagon *g* is then moved until as shown in Figs. 1 and 2, it is opposite the flap to be lowered, and it is then fixed. The workmen carried on the wagon then release the outer chains, that is, *k¹* and *k⁴*, of the flap to be moved, from the line, fasten them to the winding drums *h* and *h¹* and draw up these chains tightly, until the struts *e* (Figs. 2 and 4) as hereafter described, are automatically released. Then the chains are, by the help of the drums, slowly paid out, and the flap *c* is slowly lowered on to the sill *a*, that is into the position *c¹* (Fig. 4). If the flap is to be raised, then the two inner chains of the respective flap, that is *k²* and *k³* in Figs. 1 and 2, are fastened to the winding drums *h* and *h¹*, the outer chains being left on the line. By drawing in the chains *k²* and *k³* the flap is raised and at the same time the struts *e* are also raised. As soon as the flap is in the upright position the struts *e* take up their original position as hereinafter described. The

chains k^2 and k^3 can then be released from the drum and fastened on the line, which latter is then again lowered on the river bed. The automatic release and lowering of the struts e with the flap c as well as the arrangement of the struts in their supporting position on the closing of the flap will now be described with respect to Figs. 5 and 6.

Close to the point of support of the strut 10 on the flap is fitted a double armed lever l (Fig. 5) on the flap c . The outer chains k^1 and k^4 are then each fitted on the arm of the lever l most remote from the said point of support, for example the chain k^4 with the 15 loop l^1 of the lever l (Fig. 5), while the inner chains k^2 and k^3 are each connected with the arm of the lever closest to the point of support, for example k^3 with the loop l^2 . The 20 end of the latter lever arm reaches to the point of support of the strut e .

When for the purpose of lowering the flap on the sill the outer chains k^1 and k^4 are wound up, these chains gradually take up the pressure exerted by the water on the 25 flaps and the struts are unloaded. At the same time the levers l , since the chains k^2 and k^3 can give, are successively rotated into the position shown in Fig. 5, and the struts e are released by the levers l which 30 bear on a roller e^4 on the struts. The flap can now be lowered, which is effected by means of the water pressure as the chains are paid out. The flap c thus comes into the position c^1 (Fig. 4) and at the same time 35 the struts into the position e^1 , to which the latter are led by the nose pieces n , fitted on both sides of the struts, and the pivot o .

In drawing up a flap from the position c^1 into the position c , which is effected by 40 winding in the inner chains k^2 and k^3 , the lever l turns in the opposite direction so that the extension w of the strut e can rest upon the part v of the flap c when the strut is raised to the position e . The strut thus 45 falls into its original position of support in which it is secured by the noses e^2 and e^3 on the extension w .

In order that the guiding of the struts e may be assured in every position of the flaps 50 and the struts be insured against slipping out of the guide nose pieces n , the latter are each provided close to their edge with a slot n^1 . These slots n^1 serve to guide a pin p arranged between the guide nose pieces, this 55 pin retaining the strut e in the guide nose pieces.

Figs. 7 and 8 show another method of carrying out the arrangement for the release of the strut e . The lifting parts of the flaps are here reduced to two, and with a short flap, to 60 one, and firmly fixed to the flap at q . The release of the struts e from their active supporting position takes place in this case by means of a special connection to the lever r , rotating it with the spindle s fitted on the flap c ,

so that the nose piece t on the spindle presses the struts out of their position of support and releases them. On lowering the connection to the lever r the nose pieces t are moved back into their former position by 70 means of a spiral spring u acting on the spindle s and the supporting position thus left free. The arrangement described is for a greater height of lock, of for instance, about 2 meters. For smaller ones the arrangement can be simplified; for example, with 75 smaller heights of locks, flaps are sufficient with only one strut, and consequently with only one lever l and one nosepiece t . Also one or two runners may be used for the 80 aerial line, while with larger apparatus still more support must be given. With a considerable width of stream intermediate supports for the aerial line may be necessary and with a good height of lock the lifting 85 chains, which in this case become heavier, must, in order to facilitate being hauled up, be extended by lighter chains, which would then only serve for laying hold of them. The wagon g may be driven electrically, as 90 shown in the drawing.

What I claim as my invention and desire to secure by Letters Patent is:—

1. Apparatus for raising and lowering separately the flaps of a water gate consisting of 95 an aerial line over the gate, a wagon on the line, means for moving the wagon over any desired flap, raising and lowering mechanism on the wagon and detachable connections from the flap to the said mechanism.

2. In apparatus for raising and lowering the flaps of a water gate, an aerial line, a traveling wagon on the line, raising and lowering mechanism on the wagon, connections attached at one end to the flaps and lifting 100 means to which the connections are secured at their other ends.

3. In apparatus for raising and lowering the flaps of a water gate, an aerial line, a traveling wagon on the line, raising and 105 lowering mechanism on the wagon, connections attached at one end to the flaps, a line to which the connections are secured, lying when relaxed across the river bed, and extending mechanism at the end of the line to 110 stretch it and raise the connections.

4. In apparatus for raising and lowering the flaps of a water gate, an aerial line, a traveling wagon on the line, raising and lowering mechanism on the wagon, detachable 115 connections to the flaps, and struts in the river bed supporting the flaps and brought into and out of supporting position by the said connections.

5. In apparatus for raising and lowering 120 the flaps of a water gate, an aerial line, a traveling wagon on the line, raising and lowering mechanism on the wagon, hinged struts supporting the flaps, levers on the flaps acting on the end of the struts to re- 125 130

lease them, and connections from the lever at each side of the fulcrum to the raising mechanism.

6. In apparatus for raising and lowering the flaps of a water gate, an aerial line, a traveling wagon on the line, winding drums on the wagon, hinged struts supporting the flaps, two armed levers on the flaps acting on the end of the struts to release them, a raising connection from the lever at the strut side of the fulcrum, a strut releasing and lowering connection from the opposite side of the fulcrum, and means for raising the free ends of the connections within reach of the wagon.

7. In apparatus for raising and lowering

the flaps of a water gate, an aerial line, a traveling wagon on the line, winding mechanism on the wagon, hinged struts supporting the flaps, guiding pieces on the flaps to retain the struts during raising and lowering of the flaps, means for releasing the ends of the struts and connections from the flaps to the winding mechanism effecting the release of the struts and the raising and lowering of the flaps.

In witness whereof I have hereunto set my hand in the presence of two witnesses.

GOTTLIEB LÜSCHER.
